LIQUID FUEL BURNER

Willis B. Garner and Henry R. Carter,
Turkey, Tex.

Application January 7, 1938, Serial No. 183,905

4 Claims. (Cl. 158—70)

This invention relates to a liquid fuel or oil burner.

The invention has for its object to provide, in a manner as hereinafter set forth, a burner of the class referred to including new and improved means for directing the flame upwardly and for spreading the flame for heating and cooking purposes.

The invention has for a further object to provide, in a manner as hereinafter set forth, a burner of the class referred to including a burner element so constructed to increase the amount of heat units from the fuel when the latter is combusted.

15 The invention has for a further object to provide, in a manner as hereinafter set forth, a burner of the class referred to including spaced superposed flame spreaders and with one being adjustable relative to the other.

20 Further objects of the invention are to provide, in a manner as hereinafter set forth, a liquid fuel or oil burner which is comparatively simple in its construction and arrangement, strong, durable, compact, readily assembled, thoroughly efficient 25 in its use and comparatively inexpensive to manufacture.

To the above ends essentially and to others which may hereinafter appear, the invention consists of the novel construction, combination and arrangement of parts as will be more specifically referred to and as illustrated in the accompanying drawings wherein is shown embodiments of the invention, but it is to be understood that changes, variations and modifications may be resorted to which fall within the scope of the invention as claimed.

In the drawings:—

Figure 1 is a side elevation of a liquid fuel or oil burner in accordance with this invention,

40 Figure 2 is a section on line 2—2, Figure 1,

Figure 3 is a section on line 3—3, Figure 1,

Figure 4 is a fragmentary view in side elevation of the burner element,

Figure 5 is a section on line 5—5, Figure 4,

45 Figure 6 is a fragmentary view in elevation of the central portion of a combined flame spreader, fuel trap and distributing pipe carrier,

Figure 7 is a side elevation of a modified form 50 of burner in accordance with this invention,

Figure 8 is a section on line 8—8, Figure 7,

Figure 9 is a section on line 9—9, Figure 8,

Figure 10 is a section on line 10—10, Figure 9, and

55 Figure 11 is a top plan illustrating the manner

in which the top edge of the distributing pipe supporting means is formed.

With reference to Figures 1 to 6, the burner illustrated thereby is generally indicated at 12 and it includes a combined horizontally disposed fuel trap, flame spreader and fuel distributing pipe carrier element 13, a fuel distributing pipe 14, a tubular burner element 15, an upper flame spreader element 16 and an adjustable support 17 for the spreader 16. The body portions of 5 the carrier 13 and spreader 16, indicated at 13^a, 16^a respectively are of circular contour. The body portion 13^a of the spreader 16 is of substantially dished or saucer shape form. The burner element 15 is in the form of an annulus. The body 10 portion 13^a of the carrier 13 is of concave contour diametrically thereof. The body portion 16^a of the spreader 16 includes a central part 18 of convex contour diametrically thereof. The spreader 16 includes an annular flat flange 19 which extends laterally from the bottom of the part 18. The spreader 16 is of greater diameter than the carrier 13.

The bottom 20 of the body portion 13^a of the carrier 13 is formed with a large axial opening 21 and secured to the wall of opening 21 is a vertically disposed sleeve 22 having its top edge provided with diametrically opposed semi-circular cut-outs 23. The sleeve 22 is of a height to extend above the body portion 13^a of the carrier 13, forms a support for the fuel distributing pipe 14, as well as correlating with said body portion 13^a to form an annular trap 23^a for the fuel. The sleeve 22 provides the inner wall of the trap. 25

Pipe 14 seats in and is suitably secured to the 30 edges of the cut-outs 23. The pipe 14 extends laterally in opposite directions with respect to the sleeve 22 and has its ends merging into the inner side of the burner element 15, as indicated at 24. The pipe 14 is disposed diametrically with 35 respect to burner element 15, has its ends open into such element, and is formed centrally thereof with a depending tubular intake stem 14^a passing downwardly through the center of sleeve 22 to a point below the lower end of the latter.

The burner element 15 is in the form of an annulus of an outer diameter slightly less than the largest diameter of the carrier 13. The top of element 15 is provided circumferentially thereof with spaced aligned grooves 25, gradually 40 decreasing in depth and width from their transverse medians to the ends thereof. The grooves 25 are of a length to extend on opposite sides of the element 15. The latter in its top is formed 45 with a circular row of spaced openings 26, and 50

55

each opening establishes communication between the center of a groove 25 and the interior of the tubular body 27 of the element 15. The grooves act to direct liquid fuel to the carrier for a purpose to be referred to. The spreader 16 is superposed with respect to the burner 15 and is spaced from the latter. The burner 15 is superposed with respect to and is spaced from the body 28 of the carrier 13. The sleeve 22 of the carrier 13 extends into the element 15.

Anchored at its lower end to the pipe 14 centrally of the top of the latter is a supporting means 17 for adjustably supporting the spreader 16. The latter centrally thereof is provided with an opening 30. The means 17 consists of a threaded rod 31, a stop nut 32 engaging with the rod 31 and a clamping nut 33 which also engages with rod 31. The latter extends up through the opening 30 in the spreader 16. The nut 32 abuts against the lower face of the part 18 of the spreader 16. The nut 33 is to abut the upper face of the part 18 of the spreader 16. The nut 32 provides for elevating and lowering the spreader 16 relative to the element 15.

Connected to the lower end of stem 14^a by a coupling 14^b is one end of an oil feed line 36 leading from a source of supply not shown.

The form of burner shown in Figures 1 to 6 is of the circular type, whereas the burner shown in Figures 9 to 11 is of the oval type, and with reference to Figures 7 to 11, the burner illustrated thereby is generally indicated at 35.

The burner 35 includes a combined fuel trap, flame spreader and fuel distributing pipe carrier element 36 which is of oblong contour and of concave contour in transverse and lengthwise sections, a tubular oval shaped burner element 37 which has its ends and sides arranged inwardly with respect to the ends and sides of the carrier element 36, a cruciform shaped fuel distributing pipe 38 arranged within the element 37 and a flame spreader element 39 of oval contour of greater length and of greater width than the carrier 36.

The body portion 40 of the carrier 36 is of substantially dished or saucer-shape form and provided with an opening 41 intersected by the longitudinal and transverse medians of the carrier. Secured to the edge of the opening 41 is a vertically disposed sleeve 42 having its top edge formed at equi-distant spaced points with semi-circular cut-outs 43 in which are seated the branches of the fuel distributing pipe 38. The latter is suitably secured to the edges of the cut-outs 43 by welding or otherwise. The sleeve 42 is of a height to extend above and correlates with the body portion 40 to provide a fuel trap 42^a. The sleeve 42 forms the inner wall of the trap 42^a.

The element 37 is formed of a tubular body 44 of oval contour and has its upper face at its sides and ends formed with spaced circumferentially extending grooves 45 of the same form as the grooves 25. The top of body 44 is provided with a row of spaced ports 46 of the same arrangement with respect to the grooves 45 as the ports 26 are arranged with respect to the grooves 25.

The pipe 38 is formed of four branches 47, 48, 49 and 50. The branches 47, 48 are disposed in inner endwise aligned relation. The branches 49, 50 are arranged in inner endwise aligned relation. The branches 47, 48 are of greater length than the branches 49, 50. The inner ends of the branches merge into each other. The outer ends 75 of the branches 47, 48 merge into the inner sides

of the ends of the element 37. The outer ends of the branches 49, 50 merge into the inner sides of the sides of the element 37. The outer ends of the branches of the pipe 38 open into the body 44 of the element 37.

The spreader 39 is formed of a dome shaped part 51 merging at its bottom into an endless outwardly directed flat flange 52. The part 51 of the spreader 39 is formed with a pair of spaced aligned openings 53 each for the passage of an upstanding adjustable supporting means for spreader 35. The supporting means are indicated at 54 and are of like form and each consists of a vertically disposed threaded rod 55, a stop nut 56 engaging with the rod. The rods extend upwardly through the openings 53. The lower ends of the rods are anchored to the branches 47, 48 of the fuel distributing pipe 38. The nuts 56 bear against the inner face of the part 51 of spreader 39. The nuts 57 bear against the outer face of the part 51 of the spreader 39. The function of the nuts 56, 57 is the same as the function of the nuts 32, 33 respectively.

Connected to the points of mergence of the branches 47, 48, 49 and 50 of the distributing pipe 38 is the upper end of a depending tubular fuel intake stem 38^a which passes through the sleeve 42 to a point below the latter. The stem 38^a is disposed axially of the sleeve 42 and has its lower end connected by the coupler 38^b to a supply delivery line 58 leading from a source of supply not shown.

The connection of the fuel distributing pipe to the carrier, to the burner element and to the oil feed or supply line provides for the suspension of the carrier and burner element.

The burner elements are endless. As to the operation of the burner, it will be assumed that the burner is inactive and when in such condition, the carrier element is to receive a body of liquid fuel which is ignited to cause the combustion of the fuel fed to the openings in the burner element whereby a continuous operation of the burner is had until the fuel supply is cut off.

The liquid fuel is supplied through the openings and directed by the grooves of burner element into the carrier element.

The carrier element 13 or 36 is held up by any suitable means, preferably from the grates 50 in a stove, and upon the grates is placed a small body of clay, but the center of such body is formed with an opening for the draft to come up through, at this point an element 13 or 36 is placed on the clay body. The burner element is 55 then positioned relatively to the element 13 or 36, and in this connection, the pipe 14 is seated in the top of sleeve 22 and with its intake stem depending through the sleeve, or the pipe 38 is seated in the top of sleeve 42 and with its intake 60 stem depending through sleeve 42. The stems of the pipes 14, 38 are to be arranged to extend down through the central opening in the clay body referred to and one connected to the feed line 34 and the other to the feed line 58.

What we claim is:

1. In a liquid fuel burner, a stationary combined fuel trap, lower flame spreader and carrier element formed of a substantially dished shape body portion provided centrally of its bottom with an opening and an integral vertical sleeve registering with said opening and extending above the top of said body portion, said sleeve constituting a support, a horizontally disposed endless tubular burner element arranged above and dis-

posed inwardly with respect to the perimeter of the carrier element, said burner element being formed throughout and centrally of its top with spaced ports, a horizontally disposed fluid fuel distributing pipe supported by the sleeve, arranged within and merging into the burner element for delivering fuel therein, said pipe suspending the burner element over and in closed spaced relation to the carrier element and including a depending intake depending through said sleeve, a fuel supply line for said pipe coupled to the lower end of said stem, an upper flame spreader element arranged over and extended in lateral relation with respect to said burner element, and means extended upwardly from said pipe for securing the upper flame spreader element with the latter and over the burner element.

2. In a liquid fuel burner, a stationary combined fuel trap, lower flame spreader and carrier element formed of a substantially dished shape body portion provided centrally of its bottom with an opening and an integral vertical sleeve registering with said opening and extending above the top of said body portion, said sleeve constituting a support, a horizontally disposed endless tubular burner element arranged above and disposed inwardly with respect to the perimeter of the carrier element, said burner element being formed throughout and centrally of its top with spaced ports, a horizontally disposed fluid fuel distributing pipe supported by the sleeve, arranged within and merging into the burner element for delivering fuel therein, said pipe suspending the burner element over and in closed spaced relation to the carrier element and including a depending intake depending through said sleeve, a fuel supply line for said pipe coupled to the lower end of said stem, an upper flame spreader element arranged over and extended in lateral relation with respect to said burner element, and means extended upwardly from said pipe for securing the upper flame spreader element with the latter and over the burner element, said sleeve having its upper end edge formed with vertical cutouts through which said pipe extends.

3. In a liquid fuel burner, a stationary combined fuel trap, lower flame spreader and carrier element formed of a substantially dished shape body portion provided centrally of its bottom with an opening and an integral vertical sleeve registering with said opening and extending above the top of said body portion, said sleeve constituting a support, a horizontally disposed endless tubular burner element arranged above and disposed inwardly with respect to the perimeter of the carrier element, said burner element being formed throughout and centrally of its top with spaced ports, a horizontally disposed fluid fuel

distributing pipe supported by the sleeve, arranged within and merging into the burner element for delivering fuel therein, said pipe suspending the burner element over and in closed spaced relation to the carrier element and including a depending intake depending through said sleeve, a fuel supply line for said pipe coupled to the lower end of said stem, an upper flame spreader element arranged over and extended in lateral relation with respect to said burner element, and means extended upwardly from said pipe for securing the upper flame spreader element with the latter and over the burner element, said burner element being of annular form, said pipe disposed in diametric relation to said burner element, said sleeve having its upper end edge formed with a pair of diametrically opposed vertical cutouts through which said pipe extends.

4. In a liquid fuel burner, a stationary combined fuel trap, lower flame spreader and carrier element formed of a substantially dished shape body portion provided centrally of its bottom with an opening and an integral vertical sleeve registering with said opening and extending above the top of said body portion, said sleeve constituting a support, a horizontally disposed endless tubular burner element arranged above and disposed inwardly with respect to the perimeter of the carrier element, said burner element being formed throughout and centrally of its top with spaced ports, a horizontally disposed fluid fuel distributing pipe supported by the sleeve, arranged within and merging into the burner element for delivering fuel therein, said pipe suspending the burner element over and in closed spaced relation to the carrier element and including a depending intake depending through said sleeve, a fuel supply line for said pipe coupled to the lower end of said stem, an upper flame spreader element arranged over and extended in lateral relation with respect to said burner element, and means extended upwardly from said pipe for securing the upper flame spreader element with the latter and over the burner element, said burner element being of oblong form, said pipe being formed of a pair of branches disposed at right angles and intersecting each other at the transverse medians thereof, said sleeve having its upper end edge formed with two pair of vertical cutouts, the cutouts of each pair being diametrically opposed, the cutouts of the pair being arranged at right angles to the cutouts of the other pair, one of said branches extending through the cutouts of one pair and the other of said branches extending through the cutouts of the other pair.

WILLIS B. GARNER.
HENRY R. CARTER.
